UNITED STATES PATENT OFFICE.

ROBERT J. GOOD, OF WATERTOWN, NEW YORK, ASSIGNOR TO THE STILES & FLADD PRESS COMPANY, OF NEW YORK.

DROP-HAMMER.

SPECIFICATION forming part of Letters Patent No. 605,544, dated June 14, 1898.

Application filed February 20, 1897. Serial No. 624,492. (No model.)

To all whom it may concern:

Be it known that I, ROBERT J. GOOD, a citizen of the United States, and a resident of the city of Watertown, in the county of Jefferson 5 and State of New York, have invented certain new and useful Improvements in Drop-Hammers, of which the following is a specification.

This invention relates to improvements in drop-hammers; and it is the purpose of the 10 invention to provide a simple, efficient, and easily-controlled means for operating the hammer.

Since the essential elements of the invention may be embodied in forms of apparatus 15 showing considerable variation in other details of construction, I show in the drawings which accompany the specification several modifications, all of which embody said fundamental combination of stationary piston 20 and movable cylinder and are in this respect equivalents of each other.

Referring to the said drawings, Figure 1 is a front elevation, but with the cylinder and piston in section, of one form of my invention. 25 Fig. 2 is a vertical section of the same on a plane perpendicular to that of Fig. 1. Fig. 3 is a detail, on a larger scale, of the lower end of one of the rods which connect the hammer with the cylinder and showing the sleeve- 30 nut through which said rod works and the spring under said rod, which spring I term the "thrust-cushion." Fig. 4 is a horizontal section through the base of the stationary piston and showing the ports and valve for controlling the distribution of the steam. Fig. 35 5 is a broken front elevation of the apparatus shown in Fig. 1. Different positions of the hammer and the valve-lever are indicated by solid and dotted lines. Fig. 6 is a perspective 40 of the valve shown in Figs. 2 and 4. Fig. 7 is a front elevation, partly sectioned, of the preferred modification of the invention wherein the hammer is arranged to be controlled both automatically and by hand. 45 The piston, cylinder, ports, and valve are substantially the same as in machine shown in Fig. 1. Fig. 8 is a modification wherein the stationary piston is connected with two tubes and provided with suitable ports communicating with said tubes to distribute the operating fluid alternately to opposite sides of the

piston. Said tubes also now form the connecting-rods. Fig. 9 is a perspective view, on large scale, of the stationary piston and part of the said two tubes. Fig. 10 is a sectional elevation of another form of apparatus wherein there are several stationary pistons fixed on the anvil and the hammer is equipped with corresponding chambers which work on said pistons. The anvil is provided with ports 55 communicating with said pistons and controlled by a suitable valve. Fig. 11 is an elevation of the right end of Fig. 10. Fig. 12 is a perspective view of the valve. Fig. 13 is a plan of the apparatus, showing the hammer 60 suspended by the interlocking hooks. In this figure the upper hook is adjusted to a different position from that shown in Fig. 10. Fig. 14 is an elevation of the hammer suspended from the hook W, the standards being broken 65 away. Fig. 15 is a broken vertical section of the link and connected devices which operate the valve in Fig. 8. The section is taken so that the part of the link at the right of the slot is removed. Fig. 16 is a detail of the 70 interlocking hooks shown in Figs. 10 and 14 and just as the hammer is released.

Referring to Figs. 1 to 6, inclusive, on guides *a* of uprights *B*, which are built up in any suitable manner on the base-block *A*, 80 which carries the anvil *A'*, works the hammer *A'*. Rods *Q* work through holes in the base of the stationary piston *C*, which is bolted to the top of said uprights *B*, and connect hammer *A'* with the sleeve *F* of the movable 85 cylinder *D*. Said rods *Q* work at their lower part through nuts *S*, which are threaded into chambers made in the hammer *A'*. Said nuts *S* take the strain of the rods *Q*, which are headed at the lower end, as shown in 90 Fig. 3. Nuts *f* on the upper end of rods *Q* bear on said sleeve *F*, as shown. Springs *V* under said rods *Q* allow of a certain amount of movement of said rods in the hammer and prevent shock, and therefore I term 95 said springs "thrust-cushions." Said piston *C* is equipped with an upward extension *c*, which is finished to a true cylindrical periphery and is of a height somewhat greater than the stroke of the cylinder *D* plus the height 100 of the sleeve *F*, and said piston *C* is also preferably provided with a cylindrical wall *r*,

forming a cup, as shown. At the base of said piston C is a valve-chamber II, which connects with a port II', that extends the entire height of the said piston C and opens 5 through the top thereof. Said sleeve F has a steam-tight working fit on the said extension c. The cylinder D, which is preferably made of drawn tubing, works freely over said extension c, has a closed upper end, and is 10 sweated into or otherwise secured to said sleeve F. Said valve-chamber II is connected with ports I J, which are in turn respectively connected with exhaust and pressure-supply pipes from a boiler or other generator of 15 pressure. In said chamber II works an oscillating cylindrical valve G, provided with a port K of such size and shape as to put said port II' into communication with either the pressure-port J or the exhaust-port I, according 20 to the position of the valve. Said valve G is held against longitudinal movement by the stuffing-box G', through which works the valve-stem g'. Said valve G is operated by the arm L, which is pivotally connected with 25 the connecting-rod M, which works through a guide P, carried on the hammer A'. Adjustable collars N O are engaged by said guide P in the upward and downward movements, respectively, of said hammer, and 30 thus the valve G is operated. By varying the position of said collars N O the stroke of the hammer, and consequently the force of its blow, will be varied as desired.

The operation is as follows: When the hammer A' is down, as in Fig. 1, valve G will be 35 in the position of Fig. 4, putting pressure-port J in connection with port II' through the piston C. The delivery of steam or other fluid to said port J may be of course independently controlled by a suitable valve in the pressure-supply pipe. Now when the pressure fluid is admitted to port J it passes 40 through valve G to port II and to the cylinder D, raising the same and also the hammer A' until guide P raises collar N, and thereby oscillates the valve G to put port II' in connection with exhaust-port I. Now the pressure fluid escapes from the cylinder D, which descends along with the hammer at a rate depending on the distance the hammer falls and the degree of the exhaust-opening. Evidently 45 the collar O can be adjusted so that the descending hammer will open the valve and form a cushion to resist the descent of the hammer at any desired point above the lower end of the stroke of the hammer. Thus by varying the adjustment of the collars N O the 50 stroke of the hammer and the violence of its blow may be regulated at will.

Referring to Fig. 7, which shows the preferred arrangement for controlling the hammer, the anvil, hammer, piston, ports, and valve are arranged substantially as hereinbefore described; but the arm L' of said valve 65 G in addition to its pivotal connection with the valve-rod M', which is now preferably curved at the top, is equipped with a spring

e', a weight, or other equivalent device which tends normally to depress said arm L' and open said valve G. Said rod M' is provided 70 with the adjustable collar N', extended to the left, as shown, in order to be engaged by the hammer A' on its upward motion, and with the collar or block O', which latter is equipped with a wedge face adapted to be engaged 75 by a corresponding wedge surface d of the hammer A'. The lower part of said rod M' works through the head of a guide g', which works in a stationary box or sleeve x' and is normally pressed to the left by a spring W in 80 said sleeve x'. A forked lateral arm Y of a hand-lever X spans the neck of guide g' and by engaging a washer v' on the same when lever X is depressed draws guide g' and rod M' to the right until the end of said rod M' clears 85 the bracket f', on which the end of said rod was before supported, Fig. 7. The inner end of said lever X is extended sufficiently to come under the rod M' when same is moved off the bracket f', and a spring i' is arranged 90 to normally raise the outer end of lever X, as shown. When said hammer A' is descending, the surface d pushes collar O' and rod M' to the right, so that the end of the rod clears bracket f'. Now spring e' depresses arm L' 95 and rod M', which descends through a hole in box X' until rod M' rests on the inner end of lever X. The valve has now opened pressure to cylinder D, and the operator can control the rod M' through said lever X, and thus the 100 motion of the hammer A'. It is also evident that the operator can control the hammer A' entirely by hand independently of the automatic operation, for even if the hammer is in the position of Fig. 7 the operator can depress 105 lever X and draw rod M' off bracket f', catching the end of said rod M' on said lever X and then manipulating said rod M' and valve G as he chooses through the said lever X.

Referring to Figs. 8 and 9, the stationary piston C² is threaded on the ends of tubes A⁴ B⁴, which are threaded at their upper ends into the top block E' of the uprights, in which is formed the valve-chamber, as shown in Fig. 8. Said tube A⁴ is connected by a port c⁴ with the upper side of piston C², and said tube B⁴ is connected by a port c⁵ with the lower side of said piston. Ports c⁴ c⁵ connect said tubes A⁴ B⁴, respectively, with the said valve-chamber, as shown. The hammer A² is provided 115 with a cylindrical chamber a³, closed at the bottom by the substance of the hammer and at the top by the plate F³, provided with as many bosses and stuffing-boxes as there are tubes A⁴ B⁴, and said chamber a³ has a fluid-tight working fit on piston C². A balanced 120 piston-valve G³ is arranged in said valve-chamber, as shown in Fig. 8. The valve-stem h', which works through a stuffing-box in the usual manner, is engaged by the slotted and 125 curved upper end of rod M³. Said rod M³ works through block g², pivoted on one arm of bent lever L³. I prefer to connect the lower 130 end of rod M³ with an oscillating rod or lever

m^3 , in this manner insuring all needed freedom of lateral motion to the upper slotted end of said rod, and the end of valve-stem h' may of course carry a roller, which engages in the 5 slot of said rod M^3 to diminish friction. N^2 O^2 are adjustable collars on rod M^3 and adapted to be engaged by the hammer A^2 or a stud a^4 thereon in its upward and downward movements, respectively. The outer end of lever 10 L^3 is pivotally connected with a rod T' , and that with a hand-lever X' , treadle Z' of any usual description, or with both, as shown. A spring i^3 normally tends to depress lever L^3 and throw valve G^3 to the position of Fig. 8. 15 When hammer A^2 is down, Fig. 8, valve G^3 is in position to admit steam to above piston C^2 , and the chamber or cylinder a^3 is connected with the exhaust p^4 . Therefore the hammer rises. In rising stud a^4 lifts rod M^3 , shifting 20 valve G^3 to the left, connecting the under side of piston C^2 with the pressure and the upper side with the exhaust and causing the hammer to descend. In descending stud a^4 depresses rod M^3 and shifts valve G^3 back to 25 the original position. The operator can also control the hammer A^2 by the hand-lever X' or treadle Z' . For example, supposing the hammer A^2 to have risen, but the valve to be in the position of Fig. 8, by depressing the 30 left end of treadle Z' or by raising lever X' the operator will oscillate bent lever L^3 so as to shift the upper part of rod M^3 to the left, thereby correspondingly shifting valve G^3 to the left and admitting steam to chamber a^3 35 below piston C^2 and causing the hammer to descend. The operator can also utilize the lever X' or treadle Z' to arrest the hammer at any point.

Referring to Fig. 10, any desired number 40 of vertical hollow cylindrical columns A^5 , constituting stationary pistons, are secured on the anvil A . The bore of each of these pistons A^5 is connected with a channel B^5 , formed in said anvil, and these channels join 45 and communicate with the valve-chamber H^5 , as shown. The valve G^5 is a reciprocating balanced piston-valve, as shown. In practice I prefer to employ two stationary pistons arranged, as shown in Figs. 10 and 11, 50 within the cylinder-like portions of the uprights A^8 . The hammer A^7 is provided with cylindrical chambers D^6 , closed at the top and fitting over the pistons A^5 . Stuffing-boxes d^6 at the lower ends of said cylinders D^6 make 55 a tight working fit on the said pistons. The valve-stem g^6 is pivotally connected at the top with a lever g^8 and that in turn with a rod M^7 , which carries adjustable collars N^7 O^7 , operated by the projection P^7 on the said 60 hammer A^7 . A^9 is a hook on said hammer A^7 , arranged to engage a movable hook W^7 , which is pivoted at the lower end of an adjustable hanger W^8 . I prefer to form the hangers of two parallel bars, said hook W^7 65 being pivoted between them, as shown. Numerous holes are made through said bars, as shown, and there are corresponding holes in

the top plates A^{10} of the standards. The hanger is situated between the plates A^{10} and is fixed at any desired height by passing pins 70 or bolts through corresponding holes in the top plates and hanger. Said hook W^7 is formed with a vertical arm w^7 , which is positioned to be engaged by a cam V^6 , which is fixed on the pivot-pin, on which is also fixed 75 the lever V^8 , and also with a horizontal arm w^8 , which is connected with a backward extension of said cam V^6 by a spring w^9 , as shown. The free end of lever V^8 is connected by rod v^9 with the treadle Z^2 , and the upper 80 part of said rod V^9 is provided with numerous holes to permit of altering its connection with lever V^8 to suit the adjustment of the hanger W^8 .

In the position of Fig. 10 the pressure fluid 85 entering the valve from pipe P^6 passes into the cylinders D^6 and raises the hammer A^7 until its hook A^9 has passed clear above the hook W^7 , hook A^9 momentarily pushing hook W^7 back as the former rises. Now projection P^7 has raised collar N^7 and has shifted the valve G^5 , so as to shut off pressure from the cylinders D^6 and open them to the exhaust. The hammer now falls a little until its hook A^9 engages on hook W^7 . Now 95 the hammer A^7 remains suspended until the operator releases it by depressing the treadle Z^2 . When said treadle is depressed, lever V^8 is also depressed, turning cam V^6 to the position of Fig. 16, wherein the working face of 100 said cam pushes arm w^7 of hook W^7 to the right, thereby withdrawing said hook from hook A^9 and allowing the hammer to fall. As the hammer falls projection P^7 engages sleeve O^7 , and thereby restores valve G^5 to the position of Fig. 10. 105

Now, having described my improvements, I claim as my invention—

1. The combination in drop-hammer apparatus, of a movable cylinder, a hammer operatively connected therewith, a stationary piston provided with a steam-passage delivering into the cylinder, a chamber communicating with the said steam-passage, a three-way valve in said chamber controlling the movement of steam through said passage, and devices on said hammer adapted to throw said valve, substantially as described. 110

2. The combination in a drop-hammer apparatus, of a movable cylinder constructed 120 of tubing with a spherical end and a stationary ported piston therein, substantially as described.

3. The combination in a drop-hammer apparatus, of a stationary ported piston, a valve 125 controlling the distribution of the operating fluid through said piston, a cylinder adapted to work on said piston, a hammer operatively connected with said cylinder, a valve-operating rod, and adjustable collars thereon 130 adapted to be actuated by the hammer, substantially as described.

4. The combination in a drop-hammer apparatus of the type described, of a movable

- 5 cylinder consisting of a closed-end tube, a stuffing-box sleeve on the open end of said tube and provided with bosses, a hammer, and rods connecting said hammer with said stuffing-box sleeve and said rods being threaded at one end and headed at the other end, substantially as described.
- 10 5. The combination in a drop-hammer apparatus, of the type described, of a movable cylinder, a hammer, rods connecting the hammer with the cylinder, chambers in the hammer in which the ends of said rods work, and thrust-cushions in said chambers, substantially as described.
- 15 6. The combination in a drop-hammer apparatus, of a hammer, a wedge surface thereon, a valve controlling the movement of the hammer, a valve-operating rod, a stationary support for said rod, adjustable collars on 20 said rod and at least one of said collars having a wedge surface adapted to be engaged by the wedge surface on the hammer, whereby the rod is pushed off the support, substantially as and for the purpose described.
- 25 7. The combination in a drop-hammer apparatus, of a hammer, a wedge surface thereon, a valve controlling the movement of the hammer, a valve-operating rod, a stationary support for said rod, adjustable collars on 30 said rod at least one of which has a wedge surface adapted to be engaged by the wedge surface on the hammer for pushing the rod off the support, a lever controlled by the operator and adapted to receive and support said 35 rod, whereby the operator may control the valve independently of its operation by the

movement of the hammer, substantially as described.

8. The combination in a drop-hammer apparatus, of a hammer, a trigger device for 40 sustaining the hammer, means controlled by the operator for throwing the trigger device to release the hammer, and a spring tending to throw the said trigger device in the opposite direction to that of release, substantially 45 as described.

9. The combination in a drop-hammer apparatus, of a hammer, a hook thereon, a vertically-adjustable movable hook, a spring adapted to press the movable hook into 50 engagement with the hook on the hammer, and devices controlled by the operator for releasing the movable hook from the hook on the hammer, substantially as described.

10. The combination in drop-hammer apparatus, of a hammer, a hook thereon, a movable hook adapted to engage with the hook on the hammer, a cam for releasing the movable hook, a spring for moving the movable hook in the direction opposite to that of release, and devices controlled by the operator 55 for moving the cam so as to release the movable hook, substantially as described.

In testimony that I claim the foregoing as my invention I have signed my name, in presence of two witnesses, this 1st day of February, 1897.

ROBT. J. GOOD.
